BREAKER STRIP CONSTRUCTION

Lester H. Hinkel and John R. Prosek, Evansville,
Ind., assignors to International Harvester Com-
pany, a corporation of New Jersey

Application January 14, 1950, Serial No. 138,604

2 Claims. (Cl. 220—9)

1

This invention relates to a novel type breaker strip construction for bridging the space between the inner and outer walls of a refrigerator cabinet.

It is quite common to connect the inner and outer walls of a refrigerator cabinet with breaker strips composed of a low heat conducting material. In more recent designs, the breaker strips have been constructed in transversely curved sections and secured to inner and outer wall flanges which are disposed in different planes. The large sections of insulating material disposed between the inner and outer walls usually terminates at the flange located nearest the back of the refrigerator. This leaves a space between the breaker strip and the insulating material, which is usually filled by inserting a separate piece of insulating material. This extra piece of insulation causes increased material and labor cost in the manufacture of the article. If this space is not filled with insulating material, temperature differential between the breaker strip surface in contact with the cold cabinet air and the cabinet outer wall causes convectional air currents to be set up under the breaker strip. The outer wall will be cooled by the air circulation which causes condensation on the outer wall and a substantial heat loss between the outer and inner walls.

The primary purpose of this invention is to provide air baffles on the under side of a breaker strip so that air circulation under the breaker strip will be reduced.

Another object is to provide a transversely curved breaker strip construction which will eliminate the necessity of inserting a separate piece of insulating material under the breaker strip.

Still another object is to provide a breaker strip with rib like extensions on one side which will strengthen the breaker strip.

Other objects of the invention will appear from the following description and claims taken in connection with the accompanying drawings forming a part of the application in which:

Fig. 1 is a front view of a refrigerator cabinet utilizing the present invention and showing the food storage compartment door in open position.

Fig. 2 is an enlarged sectional view taken on line 2—2 of Fig. 1.

Fig. 3 is a rear view of a part of the breaker strip.

Referring specifically to the drawing for a detailed description of the invention, numeral 10 designates a refrigerator cabinet comprising an inner shell 11 and an outer shell 12 with heat insulation material 13 therebetween, a door 14

55 hingedly supported by hinges 15 on said outer shell and a lower front cover portion 16.

The forward marginal edge of the outer shell 12 is bent back over itself and then inwardly as indicated at 17 to form a channel 18 having spaced apart flanges or extensions 19 and 20. The forward marginal edge of the inner shell 11 is angled over to form an inwardly projecting flange or extension 21 with a second flange 22 extending at right angles to the flange 21. The insulating material terminates in substantially the same vertical plane that the flange 20 lies in, thus leaving a space between the vertical planes that flanges 19 and 20 lie in, into which breaker strip 23 fits in the manner hereinafter described.

The preformed breaker strip 23 is fashioned from a low heat conducting plastic or fibrous material of the non-hygroscopic and non-metallic type, and fashioned so as to provide a transversely curved contoured portion proximate one edge thereof, substantially as illustrated in Fig. 2. Such member may be fabricated in a plurality of sections and then installed end to end around the door opening, but in the illustrated embodiment, such member is fashioned so that only one such section is required on each side and one each on the top and bottom of the door opening.

30 On the under side of the breaker strip 23 are transversely extending ribs 25 and longitudinally extending ribs 26. In the illustrated embodiment these ribs are shown as part of the preformed breaker strip, but if desired, they could be separate members which are either attached to or placed under the breaker strip. Any number of ribs could be provided, but as seen in Fig. 3, the transverse ribs 25 are arranged in pairs spaced approximately $\frac{1}{2}$ " apart with approximately 6" between pairs and the longitudinal ribs 26 extend 35 between the pairs of transverse ribs with one rib 26 located approximately midway between the inner and outer edges of the breaker strip 23 and a second rib 26 located adjacent the outer edge of 40 said breaker strip. The ribs 25 and 26 are relatively thin and extend down into contact with the insulating material 13. A slight clearance is provided between the ribs and the flanges 20, 21, 22 and the channel 18 to allow for variation of 45 inner and outer shell dimensions. The ribs divide the space under the breaker strip 23 into rectangular sections or air pockets 27 and act as air baffles for reducing air circulation under the breaker strip. These ribs also serve to strengthen 50 the breaker strip.

Between each pair of transverse ribs 25, the breaker strip is fashioned with a turned in lip of flange 24 along its inner edge and a rib-like abutment 28 spaced inwardly from its outer edge. Spring clips 29 are placed between said ribs for holding the breaker strip in place and are fashioned from some resilient material such as spring steel with an inwardly bent portion 30 proximate one end and a large radial curved portion 31 on the opposite end. Spaced from portion 30 is a bent up portion 32 and between this bent up portion and end portion 31 is a flat portion 33.

In assembling the breaker strips in the cabinet, the spring clips 29 are first positioned so that bent up portion 32 contacts abutment 28 on the breaker strip and curved end portion 31 is forced into abutting relation with the flange 24 causing a slight loading of portion 29 of the spring clip. The assembled breaker strip and spring clips are then pushed into channel 18, causing the inwardly turned portion 30 to become loaded which tends to rotate said clip about a fulcrum at the point where the clip contacts abutment 28, thus transferring the force through the flat portion 33 and curved portion 31 to the lip 24. This forces the outer edge of the breaker strip up against flange 19 and the inner edge down against flange 21 and holds the breaker strip securely in place.

From the foregoing it will be apparent that there is provided a breaker strip assembly which is easy to install, is inexpensive and rugged, will cut down heat loss from between the inner and outer shells of a refrigerator cabinet and eliminate the necessity of fitting insulation under the breaker strip.

While one embodiment of the invention has been described for the purpose of illustration, it should be understood that various modifications may be made without departing from the spirit of the invention or the scope of the appended claims.

What is claimed is:

1. In a refrigerator cabinet, spaced inner and outer walls having edge portions bent inwardly toward each other, said edge portions disposed in different planes, heat insulating material disposed between said walls and terminating in approximately the plane of the bent-in edge portion nearest the back of said cabinet, a transversely curved breaker strip member bridging the space between said inner and outer walls and enclosing a space between said breaker strip and

said insulating material, said breaker strip member provided with longitudinally extending ribs and transversely extending ribs which extend therefrom into contact with said insulating material, said transversely extending ribs arranged in spaced apart pairs, said longitudinally extending ribs connecting said pairs, said space being divided into separate air pockets by said ribs so that air circulation in said space is prevented, and detachable resilient members positioned between each pair of said transversely extending ribs for securing the breaker strip member to said edge portions.

2. In a refrigerator cabinet having spaced apart inner and outer walls with insulation disposed therebetween, a transversely curved breaker strip, a plurality of ribs mounted longitudinally substantially at each edge on the concave side of said breaker strip, means associated with said walls and said ribs for mounting said breaker strip to abut said walls whereby a space is formed between said insulation and the concave side of said breaker strip, a second plurality of ribs mounted transversely in spaced apart pairs at spaced intervals on the concave side of said breaker strip, a third plurality of ribs mounted longitudinally in spaced apart pairs between each pair of said second plurality of ribs on the concave side of said breaker strip, said second and third plurality of ribs having a depth sufficient to cause the edges thereof to abut said insulation whereby said space is divided to form a plurality of second spaces and the curvature of said breaker strip is maintained.
